[57] CLAIM

The ornamental design for a traction device, as shown and described.

DESCRIPTION

FIG. 1 is a front view of the traction device of the present invention;

FIG. 2 is a rear view of the traction device of FIG. 1;

FIG. 3 is a right side view of the traction device of FIG. 1;

FIG. 4 is a left side view of the traction device of FIG. 1;

FIG. 5 is a top view of the traction device of FIG. 1;

FIG. 6 is a bottom view of the traction device of FIG. 1; and,

FIG. 7 is a left side elevational view of the traction device of FIG. 1, shown in an alternate position of use.

The broken line showing of a portion of a vehicle is for illustrative purposes only and forms no part of the claimed design.
